UNITED STATES PATENT OFFICE

CORWILL JACKSON, OF CHICAGO, ILLINOIS

TAMPER AND LIKE IMPACT TOOL

Original application filed December 22, 1927, Serial No. 241,861. Patent No. 1,716,638, dated June 11, 1929.
 Divided and this application filed December 6, 1928. Serial No. 324,306.

This invention relates to an improved tool or machine for tamping the ballast of railway ties and the like such as illustrated in my application for Letters Patent, Serial No. 5 241,861, filed December 22, 1927, Patent No. 1,716,638, June 11, 1929, this being a division of that application.

The main object of this invention is to provide a tool or machine of this class which is 10 very efficient and easily manipulated, enabling the accomplishment of a large amount of work with a minimum of effort on the part of the workman.

Objects relating to details and economies 15 of construction and operation of my invention will appear from the description to follow. The invention is defined and pointed out in the claims.

A structure which is a preferred embodiment of my invention is illustrated in the accompanying drawing, in which:

Fig. 1 is a side elevation view of a tool for tamping railway ties embodying the features of my invention partially in section on line 25 1—1 of Fig. 2.

Fig. 2 is an end elevation view.

The structure illustrated in the accompanying drawing comprises a body member 1 of a general inverted T-shape having a handle 2 connected to the upper end thereof. Each horizontal arm 3 is provided with a cylinder head 4 into which the cylinders 5 are threaded.

The plungers 6 are provided to coat with the impact members 7 which have heads 8 within the cylinders, the impact members being extended through the end members 13 of the cylinders and being returned and resiliently supported by the coiled spring 9.

The tamping blades 10 are mounted on the 40 outer ends of the impact members.

The source of actuating fluid and the control valve mechanism are not illustrated but suitable connections for such fluid are provided at 11 and 12.

It will be understood that the valve mechanism is such that the plungers are rapidly reciprocated, imparting a series of blows to the impact members and thereby rapidly vibrating the blades.

The tool or machine is easily manipulated,

the blades being spaced so that they may be placed astride a tie and by a rocking movement, the ballast is rapidly and effectively tamped from both sides of a tie and with comparatively little effort on the part of the 55 operator.

I have illustrated and described my improvements as I have embodied the same in a tie tamper. I have not attempted to illustrate certain other embodiments or adaptations as I believe this disclosure will enable those skilled in the art to embody or adapt my improvements as may be desired. 60

Having thus described my invention, what I claim as new and desire to secure by Letters 65 Patent, is:

1. In a structure of the class described, the combination of a body member provided with a handle, a pair of pneumatic hammer cylinders mounted on said handle and provided 70 with plungers, impact members arranged to reciprocate through the lower ends of said cylinders and provided with impact heads co-acting with said plungers, coiled springs arranged within said cylinders between said 75 impact heads and the ends of the cylinders, and tamper blades mounted on the outer ends of said impact members in opposed relation.

2. In a structure of the class described, the combination of a body member provided with 80 a handle, a pair of pneumatic hammer cylinders mounted on said body and provided with plungers, impact members operatively associated with said plungers, a return spring for said impact members, and tamper blades 85 mounted on the said impact members.

3. In a structure of the class described, the combination of a body member provided with a handle, a pair of impact engines mounted on said body, impact members operatively associated with said impact engines, a return spring for said impact members, and tools mounted on the said impact members. 90

In witness whereof I have hereunto set my hand. 95

CORWILL JACKSON.
